US0D1063387S

(12) **United States Design Patent** (10) **Patent No.:** **US D1,063,387 S**
(45) **Date of Patent:** **** Feb. 25, 2025**

(54) **CONTAINER**

(71) Applicant: **ShenZhen YiHong Technology Co., LTD**, Guangdong (CN)

(72) Inventors: **Chunlong Qiu**, ShenZhen (CN); **Xiao Zhang**, ShenZhen (CN)

(73) Assignee: **ShenZhen YiHong Technology CO., LTD**, ShenZhen (CN)

(**) Term: **15 Years**

(21) Appl. No.: **29/970,198**

(22) Filed: **Oct. 27, 2024**

Related U.S. Application Data

(62) Division of application No. 29/953,918, filed on Jul. 24, 2024, now Pat. No. Des. 1,055,518.

(51) **LOC (15) Cl.** **09-04**

(52) **U.S. Cl.**

USPC **D3/307**; D3/282

(58) **Field of Classification Search**

USPC D3/272, 273, 276, 295, 302, 304, 305, D3/306, 307, 308, 309, 310, 311, 312, D3/313, 314, 315, 318, 319, 328; D6/683, 655, 672, 705, 705.6, 705.7, 706, D6/574; D19/75, 86, 95, 99; D7/602; D32/37; D30/161

CPC B65D 1/22; B65D 81/3825; A47B 87/02; B62B 3/16; B25H 3/02
